UNITED STATES PATENT OFFICE

JOHN H. ASCHER, OF WELLSBURG, IOWA

AUTOMATIC BROODER-HOUSE CHUTE

Application filed September 17, 1929. Serial No. 393,216.

This invention relates to an automatic brooder house chute and has for its prime object to provide means for automatically closing the door at a desired time.

5 Another very important object of the invention resides in the provision of an apparatus of this nature, whereby an alarm clock is utilized for releasing a catch so that the door may gravitate to a closed position, and 10 means whereby, as the door approaches a closed position, it will shut off the alarm clock.

A still further very important object of the invention resides in the provision of an 15 apparatus of this nature, which is simple in its construction, inexpensive to manufacture and install, compact and convenient, not likely to easily get out of order, is easy to manipulate, and otherwise well adapted to the 20 purpose for which it is designed.

This invention accordingly consists in the features of construction, combination of parts, and in the unique relation of the members and in the relative proportioning and 25 disposition thereof, all as more completely outlined herein.

To enable others skilled in the art to fully comprehend the underlying features thereof that they may embody the same by the numerous modifications and structures and relations contemplated by the present invention, drawings depicting a preferred form have been annexed as a part of this disclosure and in said drawings, like characters of reference 35 denote corresponding parts throughout all of the views, of which:

Figure 1 is a fragmentary elevation of a brooder house showing the chute and associate mechanism.

40 Figure 2 is a sectional view taken substantially on the line 2—2 of Figure 1.

Figure 3 is a sectional view, taken substantially on the line 3—3 of Figure 1.

45 Figure 4 is a detail fragmentary elevation of the alarm clock showing the winding stem of the alarm.

Figure 5 is a detail sectional view showing the catch released.

50 Referring to the drawings in detail, it will be seen that 5 denotes the brooder house with

the vertically slideable door 6, and doorway 7. At the top of the doorway there is a pivotally mounted catch 8, engageable with hooks 9 on the upper end of the door 6, to hold the door in a raised position as shown in Figure 3. 55

A casing 10 is mounted inside of the brooder and has therein an alarm clock 11 of conventional construction including an alarm winding stem 12, and an alarm control lever 14. A cable or cord 15 is windable on the 60 stem 12 and is attached to the catch 8. A cord 16 is passed through an eye 16' and fastened to lever 14 and is also fastened to the top of the door 6 as at 17. With the parts disposed as is shown in Figures 1 and 3 particularly, 65 it will be seen that when the alarm goes off, the shaft or stem 14 will rotate, winding the cord 15 thereon, thereby releasing the catch 8 to the position shown in Figure 5, so that the door 6 may gravitate to a closed position 70 and as the door approaches a closed position, the part 16 is of such a length that it becomes taut and thereby pulls the lever 14 over to shut off the alarm. Thus it will be seen that the alarm may be set to a time after dark so 75 that when the chickens have gone to roost, the door may be automatically closed without any attention on the part of an attendant.

As the method of use and operation of the device is thought to be clear from the above 80 description, a further detailed discussion thereof is thought to be unnecessary.

It is therefore, believed that the present invention provides a simple and practical device, adapted to accomplish, among others, 85 all of the advantages and objects above set forth.

Without further analysis the foregoing will so fully reveal the gist of this invention that others can, by applying current knowledge, readily adapt it for various applications without omitting certain features that, from the standpoint of the prior art, clearly constitute essential characteristics of the 90 generic or specific aspects of this invention, and therefore such adaptations should and are intended to be comprehended as fall 95 within the meaning and range of the equivalency of the following claim. 100

What is claimed is:

In combination, a vertically slideable door, a catch engageable with the door for holding the same in a raised position, an alarm clock including an alarm winding stem, a cable attached to the stem for winding thereon, as the stem unwinds, said cable being attached to the catch, said alarm clock including a shut off lever for the alarm, a cord attached thereto and attached to the door to be loose when the door is in a raised position and to become taut when the door approaches a closed position, so as to shut off the alarm as the door comes to a close.

10

15 In testimony whereof I affix my signature.

JOHN H. ASCHER.
